US00D755767S

(12) **United States Design Patent**
Kim et al.

(10) **Patent No.:** **US D755,767 S**
(45) **Date of Patent:** ** *May 10, 2016

(54) **COVER FOR MOBILE PHONE**

(71) Applicant: **Samsung Electronics Co., Ltd.,**
Suwon-si (KR)

(72) Inventors: **Yoon-young Kim**, Seongnam-si (KR);
Min-a Oh, Gwangju-si (KR)

(73) Assignee: **Samsung Electronics Co., Ltd.,**
Suwon-si (KR)

(*) Notice: This patent is subject to a terminal disclaimer.

(**) Term: **14 Years**

(21) Appl. No.: **29/476,436**

(22) Filed: **Dec. 13, 2013**

(30) **Foreign Application Priority Data**

Sep. 30, 2013 (KR) 30-2013-0049577

(57) **CLAIM**

The ornamental design for a cover for mobile phone, as shown and described.

DESCRIPTION

FIG. 1 is a front perspective view of a cover for mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The dot-dash broken line shown in FIG. 1, 2 and 4 represents a boundary of the claimed design. The dash-dash broken lines depict unclaimed environment. The broken lines form no part of the claimed design.

1 Claim, 7 Drawing Sheets
